UNITED STATES PATENT OFFICE

172,692

COMBINATION HEATER AND FAN

John P. Theisen, Jacksonville, Ill., assignor to
Nesco Inc., Jacksonville, Ill., a corporation of
New Jersey

Application February 25, 1954, Serial No. 29,203

Term of patent 14 years

(Cl. D81—10)

To all whom it may concern:

Be it known that I, John P. Theisen, a citizen of the United States, residing at Jacksonville, in the county of Morgan and State of Illinois, have invented a new, original, and ornamental Design for Combination Heater and Fan, of which the following is a specification, reference being had to the accompanying drawing, forming a part thereof.

In the drawing:

Figure 1 is a perspective view of a combination heater and fan embodying my new design, looking upwardly from a position adjacent the right hand front corner of my heater and fan, showing its frontal and side appearance; and

Figure 2 is another perspective view of my new

design, looking downwardly from a point diametrically opposite the vantage point of Figure 1, showing the appearance of the rearward, top and side portions of my design.

The essential features of my design reside in the portions shown in full lines.

I claim:

The ornamental design for a combination heater and fan, substantially as shown and described.
